UNITED STATES PATENT OFFICE.

ALVIN POND AND REUBEN T. FROST, OF MARION, CONNECTICUT.

DIE FOR MAKING BOLTS.

SPECIFICATION forming part of Letters Patent No. 240,181, dated April 12, 1881.

Application filed February 19, 1881. (No model.)

To all whom it may concern:

Be it known that we, ALVIN POND and REUBEN T. FROST, of Marion, in the county of Hartford and State of Connecticut, have invented new Improvements in Dies for Making Bolts; and we do hereby declare the following, when taken in connection with the accompanying drawings and the letters of reference marked thereon, to be a full, clear, and exact description of the same, and which said drawings constitute part of this specification, and represent, in—

Figure 1, a sectional view of the upper die; Fig. 2, a perspective view of one-half the lower die.

This invention relates to an improvement in heading-dies for making that class of bolts commonly called "carriage-bolts," and such as have the neck of the bolt made angular or square, and now known as the "Clark bolt," and such as heretofore made in the dies patented to Wm. J. Clark, No. 43,669, antedated February 2, 1864. In these dies the part in which the angular neck is formed has an area substantially equal to the transverse area of the rod from which the bolt is to be made and of the cylindrical part of the cavity of the dies, so that when the round blank is placed between the cavities in the two parts of the die, and the two parts forced together, the angular portion thereof will press at four opposite points on the blank and compress it into angular shape, forcing the metal into the angles, so as to form the square portion without necessarily forcing additional metal onto the said angular part, and then, while the blank is held between the parts of the die which have shaped the neck, the head is formed, the parts of the die which hold the blank serving as the anvil on which to make the head.

A serious difficulty has been experienced in making this class of bolts, from the fact that in compressing the metal to form the neck, which must be done before the heading can take place, the metal is more or less chilled; and in the subsequent upsetting of the metal above the neck, which forms the head, what is commonly known as a "cold-shut," is frequently produced between the neck and the head, thus weakening the bolt, and frequently causing the head to break from the neck.

To overcome this difficulty is the object of this invention, which consists in the dies constructed as hereinafter described, and particularly recited in the claim.

55

A represents one half the die, in which blanks are held and the neck shaped, the other half being a duplicate thereof. In this die are two cavities, *a* *b*—the one, *a*, for the primary operation, and the second, *b*, for finishing the bolt, 60 the lower part, *c*, of the cavity *a* corresponding to the cylindrical blank. The part *d* is angular, preferably so as to form four angles, the transverse area of this portion *d* being substantially that of the cylindrical section of 65 the part *c*. At the face end of the cavity *a* the die has a countersunk portion, *e*, which is circular in transverse section, expanding from the part *d* outward.

The blank, Fig. 3, is placed between the two 70 parts of the die in the cavity *a*, its end protruding, as seen in broken lines, Fig. 1, to a sufficient extent to give metal above the part *d* of the cavity to form a complete head. The two parts of the die *a* are then forced together, 75 compressing that portion of the blank in the part *d* until the two faces of the dies meet, thus giving to the portion in the part *d* an angular shape, as in the hereinbefore-mentioned Clark bolt. Then the heading-die is forced to- 80 ward the face of the holding-die. In this heading-die *B* is the cavity *f*, having the shape of a frustum of a cone, which receives the end of the blank and upsets the metal into the part *e* of the cavity, producing the shape seen in 85 Fig. 4, and in which the enlarged portion gradually expands from the square or angular portion. Then the blank, thus prepared, is placed in the second cavity, *b*, which is of substan- 90 tially the shape used to make the Clark blank—that is to say, the part *h* corresponds to the cylindrical body of the bolt and the part *i* to the angular neck—so that when the blank (Fig. 4) is introduced into said cavity *b* it substantially fills the same, the enlarged portion 95 standing above the face of the die, the blank resting at the intersection of the angular neck with the enlarged part designated by the letter *n*, Fig. 4. Then the heading-die, in which is a cavity, *m*, corresponding to the shape of the finished head, descends upon the project- 100 ing and enlarged end of the blank and upsets

that portion upon the face of the holding-die and into the finished head.

Because the partial upsetting and expanding of the metal above the neck by the first 5 operation leaves the surface inclined to the face of the die, the "cold-shut" produced by making the upset and breaking down to a right angle at the first operation is avoided.

We claim—

10 The herein-described dies for heading bolts, consisting of a die having a cavity, *a*, consisting of a cylindrical part, *c*, the angular part *d*,

and the expanding part *e*, and the second cavity, *b*, having the cylindrical part *h* and angular part *i*, combined with a heading-die constructed with a cavity, *f*, and a finishing cavity, *m*, corresponding to the cavities *a* and *b*, respectively, substantially as described. 15
